UNITED STATES PATENT OFFICE.

RALPH R. SANDHAM, OF HARLAN, IOWA, ASSIGNOR OF ONE-HALF TO JOHN SANDHAM,
OF HARLAN, IOWA.

HAND-STAMP.

1,227,204.

Specification of Letters Patent. Patented May 22, 1917.

Application filed November 1, 1916. Serial No. 128,923.

To all whom it may concern:

Be it known that I, RALPH R. SANDHAM, a citizen of the United States, residing in Harlan, county of Shelby, and State of Iowa, have invented certain new and useful Improvements in Hand-Stamps, of which the following is a specification.

My invention relates to printing devices which are operated by hand to make the impression and parts of which are spring mounted so as to return the type-wheels to normal position after each impression, and my present improvements are particularly well adapted for hand-stamps, including what are known as check-protectors, as well as numbering and dating stamps and stamps employing letters instead of numerals.

The invention consists in the various novel combinations and arrangements of the several different parts of the apparatus, all as hereinafter fully set forth and then pointed out in the claims.

I have illustrated a type of my invention in the accompanying drawings, wherein:

Figure 1, shows a side view of my improved form of hand-stamp, with the upper part of the upper casing broken away.

Fig. 2, is a central vertical section of the device, the plane of the section being indicated by line 2—2, Fig. 1.

Fig. 3, is a perspective view of the base-frame, shown as detached, and with the type-wheel shaft, its bushings and springs mounted in place in the frame.

Fig. 4, is a central vertical section of the device, the plane of the section being indicated by line 4—4, Fig. 2.

Fig. 5, is a side view of the device in the depressed position which it assumes when pushed down by hand to print.

Referring to the drawings, in which like numbers of reference designate like parts throughout, 1 is the base-frame which is shown as made from sheet metal open at the top and on one of its sides and having an opening 2, formed in the under side and through which the set of type-wheels project slightly when making an impression. In two opposite sides of the base-frame are formed rectangular shaped guide-slots 3, in which slide vertically the respective bushings 4, in which the ends of the type-wheel shaft 5, are mounted.

The vertical sides of the respective bushings 4, are parallel and fit snugly within

the guide-slots 3, so as to slide readily up and down therein and these slots also serve to limit the range of vertical movement of the bushings and likewise the type-wheel shaft and type-wheels. This peculiar mounting also provides a smooth mechanically controlled perpendicular movement of the type-wheels in the printing operation.

The under side of each of the bushing blocks 4, is formed with a groove 6, for the reception of the upper end of the springs 7, the lower ends of which rest in the pockets 8, which are provided by the flanges 9, formed from upset parts of the material of the lower side of the base-frame. These upright flanges 9, are each notched at 10, for the passage of the bushings 4, in their vertical movements when the type-wheels are reciprocated. The flanges 9, extend a considerable distance upwardly and in fact to the highest points reached by the springs and they are of sufficient length to fully cover and house the springs and this arrangement insures a smooth action of the springs and prevents them from getting displaced.

The outer end of each of the bushing blocks 4, is formed with a rectangular shaped projection or boss 11, which fits into similarly shaped openings 12, formed in the opposite sides of the casing 13. Upon each end of the shaft is a washer 14, through which passes a screw 15, which takes into a socket 16, formed in the center of the end of the type-wheel shaft 5. By this means the ends of the type-wheel shaft are secured to the opposite sides of the upper casing 13, which is mounted to reciprocate vertically over the base-frame and the shaft is moved in response to the movements of the casing. The upper casing 13, is fitted snugly over the base-frame 1, and is practically closed upon all its four sides and the top and is provided upon its upper side with a handle 17, for depressing the casing, which through means of the described connection with the respective ends of the type-wheel shaft, is spring mounted upon the base-frame and normally the casing is held upwardly by the springs 7.

Upon the type-wheel shaft 5, are loosely mounted a suitable number of type-wheels 18, each of which is provided with a cog-wheel 19, secured to the type-wheel and each cog-wheel is engaged by a toothed finger-

wheel 20, which turns loosely upon a shaft 21, which is mounted upon the inner side of the casing 13, and extends parallel with the type-wheel shaft. The casing 13, is bent outwardly at 22, to accommodate the finger-wheel shaft 21, and this same side of the casing is formed with a series of vertical slits 23, as shown more particularly in Fig. 1. The finger-wheels project through the slits in the casing so as to be accessible from the exterior of the casing to the operator in setting the type-wheels, each of which turns independently of the others. The cog-wheels are so related to the type-wheels that the type on the peripheries of the wheels may be set in alinement, as shown in the drawings, and the line on which the type print is indicated upon the exterior of the opposite sides of the device by means 15 of contrasting marks 24. By placing the device so that the indicating marks 24, register with a certain space on the paper which is to be printed on, the location of the impression may be definitely controlled. It 20 will be noted that this indicator 24, is made on the surface of the material of the base-frame so as to form a permanent mark. This mark may be made from enamel or in any other suitable well-known manner and 25 similar marks are used at 25, upon the interior of the base-frame, as shown more particularly in Figs. 3, and 4, and these latter marks are for the purpose of assisting the setting of the type-wheels in printing alinement when the device is turned up-side-down for visible manipulation, the mark extending across the under side of the frame.

The respective ends of the shaft 21, pass through the opposite sides of the casing 13, and each end is screw-threaded for the reception of a nut 26, for locking the shaft in place. Each of the toothed finger-wheels 20, is provided with a spring tongue 27, which projects downwardly from a plate 28, which is secured to the upper part of the casing 13, and these tongues engage the finger-wheels and serve to hold them in adjusted position.

In the construction of the casing 13, in which the sides thereof which support the type-wheel shaft are disconnected from the side through which the finger-wheels project, the base-frame with its type-wheels, type-wheel shaft, bushings and springs, may be removed as a unit, by partly unscrewing the nuts 26, of the finger-wheel shaft 21, then removing the screws 15, from the opposite ends of the type-wheel shaft, and springing the sides of the casing slightly outwardly so as to release the squared projections 11, from the openings 12, in said sides of the casing.

In the upper part of the casing 13, is mounted a horizontally sliding frame 29, in one end of which is mounted a set of

inking-disks 30, while the other end is provided with a series of detents 31, for engaging the spaces between the type of the type-wheels and holding them normally in locked positions. This sliding frame 29, is 70 acted upon by a spring 32, which is placed between the inner side of the casing 13, and the frame and is coiled around a fixed stud 33, on the casing, said stud projecting into an orifice 36 in the sliding frame. The 75 end of the frame 29, bearing the inking-disks is provided with a push-piece 34, which extends through an opening 35, in the wall of the casing 13, so as to project to the outside of the casing. Normally the inking-disks are held out of contact with the type-wheels and when it is desired to ink the 80 wheels the push-piece 34, is pressed inwardly so that the detents 31, disengage the type-wheels and the ink-disks are brought 85 in contact with the type on the wheels and the type are inked by turning the type-wheels through means of the finger-wheels.

It will be noted that in my particular construction of this device, the outer casing forms a substantial and complete housing 90 for the base-frame upon which it is mounted to reciprocate and that the type-wheels in the operation of printing move within the base-frame and that the type-wheel shaft 95 is held immovable in relation to the casing 13, by the squared ends of the bushing blocks in which the type-wheel shaft is carried. In taking the device apart for the purpose of cleaning or repairing it, the 100 base-frame together with the type-wheels, type-wheel shaft, its bushings and springs, may be readily removed as a unit, in the manner herein above described, and without 105 dismounting the finger-wheels or disturbing the inking and type-wheel locking mechanism. It will also be observed that the type-wheels and the cog-wheels are assembled on the shaft between the bushings, which are of substantial size and which 110 serve to space the said wheels from the sides of the casing, as indicated in the drawings.

I wish to be understood as not limiting my invention to the particular constructions 115 of parts herein set forth, as it is manifest that various changes may be made in the several different parts of the apparatus, without however departing from the spirit of the invention.

Having thus described my invention, what I claim and desire to secure by Letters Patent is as follows:

1. In a printing device of the class described, the combination of a base-frame 125 having the opposite sides provided with vertical guide-slots, a vertically reciprocating type-wheel carrying casing spring-mounted on the exterior of said base-frame, reciprocating bushings sliding in said guide-slots 130

and being detachably connected with said casing and moving in response thereto, and a type-wheel shaft mounted in said reciprocating bushings.

5. 2. In a printing device of the class described, the combination of a base-frame having the opposite sides provided with vertical guide-slots, a vertically reciprocating casing mounted on said base-frame and the opposite sides of said casing being provided with openings registering with said guide-slots in the base-frame, reciprocating bushings sliding in said guide-slots in the base-frame and projecting through said openings in the casing, a type-wheel shaft mounted in said reciprocating bushings, and releasable fastening devices connecting the respective ends of the said shaft with the sides of said casing.

20. 3. In a printing device of the class described, the combination of a base-frame, and a type-wheel carrying casing spring mounted on said base-frame and having capacity of vertical reciprocation thereon, the opposite sides of the base-frame being provided with vertical guides, sliding bushings mounted upon opposite ends of the type-wheel shaft and fitting within the respective guides of said base-frame, the said bushings being operatively connected with the reciprocating casing and moving in response to the same, inwardly projecting flanges upon the opposite sides of said base-frame, and springs interposed between said flanges and said bushings, respectively.

25. 4. In a printing device of the class described, the combination of a base-frame, and a type-wheel carrying casing spring mounted on said base-frame and having capacity of vertical reciprocation thereon, the opposite sides of the base-frame being provided with vertical guides, sliding bushings mounted upon opposite ends of the type-wheel shaft and fitting within the respective guides of said base-frame, the said bushings being operatively connected with the reciprocating casing and moving in response to the same, the said base-frame being formed of sheet metal with the lower side 45 cut so as to form two inwardly projecting tongues or flanges and such parts being bent upwardly upon the interior of the base part so as to form spring receiving pockets, and springs interposed between said pockets and bushings, respectively.

50. 5. In a printing device of the class described, the combination of a base-frame, and a type-wheel carrying casing spring mounted on said base-frame and having capacity of vertical reciprocation thereon, the said base-frame being formed of sheet metal bent so as to form a bottom and three vertical sides with the top and one side open, a casing having its under side open and 55 mounted over said base-frame and adapted

to reciprocate vertically thereon, a set of type-wheels mounted within said base-frame and provided with a shaft having the ends thereof projecting through opposite sides of the base-frame and secured to the opposite sides of said casing so as to move vertically in response thereto, each of said type-wheels being provided with a cog-wheel, a set of toothed finger-wheels each of which engages one of said cog-wheels, mounted in the side 70 of said casing corresponding to the open side of said base-frame and projecting to the exterior of said casing for access to the finger of the operator, the lower side of said base-frame being formed with an opening 75 through which the type-wheels operate to print.

6. In a printing device of the class described, the combination of a base-frame, a vertically reciprocating casing mounted on 80 said base-frame, a type-wheel shaft mounted within said base-frame, inwardly projecting flanges upon the opposite sides of said base-frame and springs bearing against said flanges and the mountings of the type-wheel shaft and normally keeping the shaft 85 pressed upwardly.

7. In a printing device of the class described, the combination of a base-frame, and a type-wheel carrying casing spring 90 mounted on said base-frame and having capacity of vertical reciprocation thereon, the opposite sides of the base-frame being provided with vertical guides, sliding bushings having parallel vertical sides mounted 95 upon opposite ends of the type-wheel shaft and fitting within the respective guides of said base-frame, the said bushings being operatively connected with the reciprocating casing and moving in response to the same, the under side of each bushing being formed 100 with a groove, and springs interposed between said respective grooves and fixed points on the base-frame.

8. In a printing device of the class described, the combination of a base-frame having the opposite sides provided with vertical guide-slots, a vertically reciprocating casing mounted on said base-frame and the opposite sides of said casing being provided with openings registering with said guide-slots in the base-frame, reciprocating bushings sliding in said guide-slots in the base-frame and having their outer ends provided with a shoulder adapted to rest against the 110 side of said casing and projecting through the said openings in the casing, a type-wheel shaft mounted in said reciprocating bushings, and releasable fastening devices connecting the respective ends of the said 115 shaft with the sides of said casing.

9. In a printing device of the class described, the combination of a base-frame, and a type-wheel carrying casing spring 120 mounted on said base-frame and having ca- 130

- 5 capacity of vertical reciprocation thereon, the opposite sides of the base-frame being provided with vertical guides, sliding bushings having parallel vertical sides mounted upon
10 opposite ends of the type-wheel shaft and fitting within the respective guides of said base-frame, the said bushings being operatively connected with the reciprocating casing and moving in response to the same.
10. In a printing device of the class described, the combination of a base-frame, and a type-wheel carrying casing spring mounted on said base-frame and having capacity of vertical reciprocation thereon, the
15 opposite sides of the base-frame being provided with vertical guides, sliding bushings having parallel vertical sides mounted upon opposite ends of the type-wheel shaft and

fitting within the respective guides of said base-frame, the said bushings being operatively connected with the reciprocating casing and moving in response to the same, the lower ends of the respective bushing-guides being provided with angular portions and the under sides of the respective bushings being provided with angular portions conforming to those of the said guides serving to seat the bushings securely at the bottom of the guides.

In testimony whereof, I have hereunto set my hand in the presence of the two subscribing witnesses.

RALPH R. SANDHAM.
